PICKER STICK CHECK

Charles W. Kuykendall, Greenville, S. C.

Application September 10, 1952, Serial No. 308,819

5 Claims. (Cl. 139—164)

1

My invention relates to picker stick checks for looms.

An important object of the invention is to provide a picker stick check which may be applied to a conventional loom, which is of simplified construction, having parts to produce a yielding, wedging action against the picker stick to gradually arrest its movement, and which may be readily adjusted for regulating the degree of yielding wedging action.

Other objects and advantages of the invention will be apparent during the course of the following description.

In the accompanying drawings forming a part of this application and in which like numerals are employed to designate like parts throughout same,

Figure 1 is a front side elevation of the picker stick check showing the same applied to the lay of a loom,

Figure 2 is a horizontal section taken on line 2—2 of Figure 1,

Figure 3 is an enlarged horizontal section taken on line 3—3 of Figure 1,

Figure 4 is a front side elevation of the picker stick check removed,

Figure 5 is a transverse vertical section taken on line 5—5 of Figure 2, and,

Figure 6 is an enlarged transverse cross section through the picker stick and brake means carried thereby.

In the drawings, where for the purpose of illustration is shown a preferred embodiment of my invention, the numeral 18 designates the lay of a loom having the usual longitudinal slot formed therein for receiving a picker stick 11 having a picker 12. This picker stick is swung longitudinally of the lay in the usual manner.

An inverted L-shaped bracket 13 having horizontal and vertical webs 14 and 15 is provided. The horizontal web has transverse slots 16 for receiving bolts 17, tapped into the lower surface of the lay. One bracket 13 is arranged near each end of the lay.

The picker stick check is designated as a whole by the numeral 18 and is formed from a strip of stiff and resilient metal. The check includes an intermediate portion 19 and inwardly facing opposed U-shaped portions 20. Each U-shaped portion 20 includes an outer closed end 20' and forward and rear sides 21 and 22, and these sides are longitudinally inclined with relation to each other and converge toward the closed end of the U-shaped portion 20. Each side 21 is formed integral with the intermediate portion 19 and this

2

intermediate portion is offset forwardly slightly at 23, whereby the side 21 is arranged slightly in advance of the intermediate portion 19. The sides 21 and 22 of each U-shaped portion having openings 24 formed therein receiving a bolt 25 having an adjustable nut 26. By adjusting the nut 26, the sides 21 and 22 may be brought closer together or may be allowed to spring to positions a greater distance apart. Each U-shaped portion and its sides 21 and 22 are resilient.

The ends of the rear sides 22 adjacent the intermediate portion 19 are freely disposed, as shown.

Each U-shaped portion has its side 21, Figure 4, provided with a horizontal longitudinal slit 27 and a vertical slit 28. The horizontal slit 27 extends from the offset portion 23 to the slit 28. These slits form a leaf spring 29, the inner end of which is integral with the offset portion 23. It extends rearwardly slightly of the side 21. The leaf spring 29 has a free inclined end 29'.

One check 18 is mounted beneath the lay 10, near the end thereof and the intermediate portion 19 engages the vertical web 15 and is secured thereto by bolts 30.

The picker stick 11 is provided upon its opposite faces with friction pads or brakes 31. These friction pads or brakes have horizontally inclined faces 32. These friction pads or brakes are secured to the picker stick by screws 33 or the like, having their heads countersunk in the friction pads or brakes so that they will not contact with the arms of the check.

In operation, when the picker stick is moved to the right toward the outer position, the faces 32 to the right of the friction pads or brakes will slidably contact with the sides 21 and 22 and the leaf spring 29. Since the sides and leaf spring are resilient and longitudinally inclined, they will produce a yielding frictional engagement with the friction pads or brakes 31, producing a yielding braking action so that the picker stick will be brought to rest at the end of its travel. The inclined end 29 has a greater frictional engagement with the friction pad or brake 31. This will cause the picker stick to dwell just before the shuttle comes in contact with the picker stick.

When the picker stick is thrown to the left toward the inner position, the left faces 32 of the check pads or brakes 31 engage with the sides 21 and 22 of the check and the yielding brake action is applied to the picker stick which is brought to rest at the end of its stroke.

It is to be understood that the form of the in-

vention herewith shown and described is to be taken as a preferred embodiment of the same, and that various changes in the shape, size and arrangement of parts may be resorted to, without departing from the spirit of the invention or the scope of the subjoined claims.

Having thus described my invention, I claim:

1. A picker stick check comprising a resilient strip including an intermediate portion and U-shaped members carried by the intermediate portion and arranged in opposed relation, each U-shaped member including a closed end and sides, one side having a free end, said sides being longitudinally inclined and converging toward the closed end, one side being slit to form a leaf spring extending longitudinally of such side and arranged rearwardly of such side prior to engagement by the picker stick, a picker stick within the check, and brake means carried by the picker stick to engage the sides and leaf springs of the U-shaped members.

2. A picker stick check comprising an intermediate portion, resilient U-shaped members carried by the intermediate portion and extending beyond opposite sides of the same in opposed relation, the resilient U-shaped members including sides and closed ends, corresponding sides of the U-shaped members being secured to the intermediate portion, the other sides of the U-shaped members having corresponding ends freely disposed for flexure relative to said corresponding sides, the sides of the U-shaped members converging toward said closed ends, and means connecting the sides of the U-shaped members near said closed ends and adjustable to regulate the distance between the sides.

3. A picker stick check comprising an intermediate portion, resilient substantially U-shaped members carried by the intermediate portion in opposed relation, the U-shaped members including sides and closed ends, corresponding sides of the U-shaped members being secured to the intermediate portion, the other sides of the U-shaped members having corresponding ends freely disposed and being adapted to flex relative to said corresponding sides, the sides of the U-shaped members converging toward said closed ends, adjustable means connecting the sides of

the U-shaped members near said closed ends for varying the distance between the sides, a picker stick operable between the sides of the U-shaped members, and friction brake means carried by the picker stick for engagement with the sides of the U-shaped members.

4. A picker stick check comprising an intermediate portion, resilient substantially U-shaped members carried by the intermediate portion in opposed relation, the U-shaped members having sides and closed ends, corresponding sides of the U-shaped members being secured to the intermediate portion, the other sides of the U-shaped members having corresponding ends freely disposed, the sides of the U-shaped members converging toward said closed ends, a picker stick operable between the converging sides of the U-shaped members, and friction brake elements secured to opposite sides of the picker stick and having inclined converging faces for cooperation with said inclined sides of the U-shaped members and adapted to produce a wedging action with the sides of the members as the picker stick approaches said closed ends.

5. A picker stick check comprising a unitary strip including an intermediate portion and opposed substantially U-shaped members extending beyond opposite sides of the intermediate portion, the U-shaped members having closed ends arranged remote from the intermediate portion and sides which converge toward the closed ends, the U-shaped members being somewhat resilient, and adjustable means connecting the sides of the U-shaped members near their closed ends to regulate the distance between the sides.

CHARLES W. KUYKENDALL.
